Primary Examiner—Jeffrey Asch

[57] **CLAIM**

The ornamental design for the micro popcorn dispenser, as shown and described.

DESCRIPTION

FIG. 1 is a front elevational view of the micro popcorn dispenser showing my new design with the broken line showing of the popcorn box and popcorn kernels for illustrative purposes only, not forming any part of the claimed design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.
